UNITED STATES PATENT OFFICE

SEYMOUR TROY, OF NEW YORK, N. Y.

DESIGN FOR A WOMAN'S SHOE

Application filed December 11, 1930. Serial No. 37,942. Term of patent 14 years.

To all whom it may concern:

Be it known that I, SEYMOUR TROY, a citizen of the Republic of Poland, residing at New York, in the county and State of New York, have invented a new, original, and ornamental Design for a Woman's Shoe, of which the following is a specification, reference being had to the accompanying drawing, forming a part thereof.

The drawing is a side view of a woman's shoe showing my new design. The novel features of the design are to be found in the

quarter which I have shown in full lines, and more particularly in the forward portion of the quarter above the shank of the shoe. The opposite side of the shoe presents substantially the same appearance as the side shown, except for the fastening means on the ankle strap.

I claim:

The ornamental design for a woman's shoe substantially as shown and described.

SEYMOUR TROY.
